UNITED STATES PATENT OFFICE.

ALBERT HALL, OF BROOKLYN, NEW YORK.

WHIP-HOLDER.

SPECIFICATION forming part of Letters Patent No. 400,452, dated April 2, 1889.

Application filed July 26, 1888. Serial No. 281,059. (No model.)

To all whom it may concern:

Be it known that I, ALBERT HALL, of Brooklyn, in the county of Kings and State of New York, have invented certain new and useful 5 Improvements in Whip-Holders, of which the following is a specification.

The object of my invention is to provide a new and improved device for holding a whip in such a manner that its upper end cannot 10 bend over, which device is simple in construction and effective in use.

The invention consists in the combination, with a swinging link having a whip-grip on the swinging end, of a longitudinally-movable 15 rod connected with the swinging end of said link.

The invention also consists of the construction and combination of parts, as will be fully described hereinafter, and finally be pointed 20 out in the claims.

In the accompanying drawings, Figure 1 is an elevation of my improved whip-holder, parts being broken out. Fig. 2 is a top view of the same, and Fig. 3 is a horizontal sec- 25 tional view on line *x x*, Fig. 1.

Similar letters of reference indicate corresponding parts.

On the face of a board, B, a U-shaped wire, A, is applied to slide longitudinally by means 30 of suitable staples, C, the lower closed end of said wire being bent to project from the face of the board, and also bent to form a U-shaped recess, D. The upper ends of the shanks of said wire A are bent to project in the direc- 35 tion from the face of the board and form pivots E, on each of which a rubber or other gripping roller, F, or whip grip is secured. The outer ends of said pivots E project through longitudinal slots in the links H, pivoted by 40 pintles J to the face of the board. A guide- strip, K, is secured on the board and extends over the upper ends of the shanks of the wire A. By pushing the wire A upward the links H and rollers F are swung from each other, 45 as shown in dotted lines in Fig. 1, and the upper end of the whip can be inserted between the rollers, the lower part of the whip being passed into the recess D in the lower closed end of the wire A. Then said wire is

pressed downward, whereby the rollers F are 50 swung toward each other and grip on the upper or snapper end of the whip and hold the same, so that the whip is now suspended by its upper or snapper end from said rollers. When the whip is to be removed, the wire A 55 is pushed upward, whereby the rollers F are swung from each other and the whip released.

My improved whip-holder holds the whip in such a manner that it hangs vertically, and thus can keep straight when held in the 60 same, and cannot bend or twist under the actions of the moisture, &c., in the stable. As the rollers F are swung from each other before removing the whip, there is no danger 65 of tearing off the snapper.

If desired, one roller or grip may be fixed, and only one mounted to swing.

Having thus described my invention, I claim as new and desire to secure by Letters Patent—

1. In a whip-holder, the combination, with 70 the swinging whip-grip, of a longitudinally-movable wire for operating the same, substan- tially as set forth.

2. In a whip-holder, the combination, with 75 a pivoted link, of a whip-grip on the swing- ing end of the same, and a longitudinally-movable wire for swinging said link, substan- tially as set forth.

3. In a whip-holder, the combination, with 80 swinging links, of whip-grips in the swinging ends of the same, a longitudinally-movable U-shaped wire connected with the swinging ends of the links and having its lower end bent outward and provided with a recess for receiving the thicker part of the whip, sub- 85 stantially as set forth.

4. In a whip-holder, the combination, with 90 a board, D, of a longitudinally-movable wire, A, having pivots formed at its upper ends, the rollers F, mounted on said pivots, and the links H, substantially as set forth.

In testimony that I claim the foregoing as my invention I have signed my name in presence of two subscribing witnesses.

ALBERT HALL.
